Patented May 24, 1927.

UNITED STATES PATENT OFFICE.

THOMAS C. MARSHALL, OF MOUNT SAVAGE, MARYLAND.

METHOD OF MAKING TIRE CASINGS.

No Drawing.

Application filed August 29, 1922. Serial No. 585,070.

My invention relates to the production of a tire casing suitable for use as an ordinary pneumatic, or equally effective as a retreading shoe, or as an outer envelope for any 5 well-known resilient filler used as a substitute for air.

Briefly, the basic conception implies the construction of a casing composed of superposed sheets of rubber, or rubber 10 pounds, or the like, treated in a novel manner and thereafter incorporated into the casing in an entirely new manner for the purpose of forming a new article of manufacture, less expensive to make than the conventional casing, and in many ways superior thereto; all as hereinafter fully explained.

Heretofore, casings of the class under discussion have been universally constructed of alternate layers of strength members 20 composed of fabric, either conventional cross-woven, or of the so-called "cord" stock generally recognized as superior for this purpose, and unifying layers of a vulcanizable rubber medium. This unifying rubber

25 may, of course, be present in the form of a friction coating direct upon the fabric.

Referring to the well-recognized mechanics of tire design, these strength elements of the fabric (the term fabric, being 30 employed in its basic sense to denote any form of textile strength insertion) are laid up in diagonal relation with respect to the normal surface of the casing with the direction of the strands of alternating plies 35 running in opposed direction; this arrangement insuring the maximum efficiency.

Among the chief defects and objections to the use of fabric insertions in casings may be mentioned:

40 (a) The tendency of the structure to heat under the influence of internal friction, probably chiefly due to the relative movement of cord-on-cord and the radically different physical reactions of the fabric and rubber under high stresses.

(b) The relative inelasticity of the fabric content as compared to rubber, as demonstrated by the characteristic rupture of fabric insertions under sudden and severe 50 shocks—this form of accidental destruction being the most common means of ending the life of a tire.

(c) The tendency of the fabric to separate in those zones of the casing subjected to 55 the greatest amplitude of flexation, due to the lack of elasticity of the fabric and its

inability to form a perfect union with the unifying rubber.

(d) The tendency of the fabric to deteriorate and weaken in the presence of constant fatigue stress, and especially to rot away in the presence of moisture which gains access to the fabric plies through surface cuts.

(e) The difficulty experienced in repairing a break in the fabric, for the reason that splicing is impossible, and the expedient of vulcanizing in a new section is of doubtful efficiency and unsightly; and

(f) Lastly, the expense of using a considerable amount of fabric content in the casing in substitution of rubber. The cost of high grade frictioned cord fabric being, at this date, approximately three times that of the best grade of rubber, based on gross 75 weight.

Of course, it is not a new thought to construct inner tubes and a certain class of single tube tires, designed for light duty, wholly of rubber. This has been practiced both in 80 the form of tubing the stock through an annular die and by sheeting the stock and wrapping it around a mandrel. In either event, resulting in a homogeneous casing useful for certain purposes where the 85 stresses are not great or where such stresses are secondarily restrained, as in the case of an inner tube confined by an outer casing against distorting stresses. But my invention differs from this practice, radically, as 90 presently explained.

Being well cognizant of the above limitations of fabric and of a wholly rubber structure as a casing, it is the object of the present invention to overcome all of the difficulties 95 enumerated, and which have been stated at considerable length in order that the scope of my improvements may be readily distinguished from the prior art. The various objects of the disclosure will appear in the 100 following description and appended claims without resorting to a detailed summation of them.

In the description and claims, the term, "wholly of rubber," is used in the generic 105 sense to differentiate my structure from the conventional fabric insert tire, and is sufficiently embrasive to include all compounds of rubber with or without a secondary toughening filler, such as finely divided textile material, fibre, or the like, as a binder.

No drawings are appended for the reason

that those skilled in the art will readily understand the several operations and well known mechanical appliances referred to throughout the discussion.

5 In my invention, in taking the revolutionary step of eliminating the fabric content, certain fundamental principles of construction best exemplified in the modern cord tire casing, are taken advantage of. That is, the 10 rubber used in my process simulates cord fabric in that a direction of strength grain, or toughness in one direction is recognized and attained, both in the preparation of the raw material and in the fabrication of the 15 finished stock into the casing. The attainment of this strength in one direction, like cord stock, is highly desirable for the mechanical advantage gained by laying the plies helically or diagonally of the core and 20 reversing the direction of the strength grain of superposed plies, all as well understood in the art.

In the preparation of stock for my casing the ingredients are compounded, in the 25 presence of suitable known chemical elements to build up desired physical characteristics, on the usual hot mill until thoroughly mixed and the "batch" then treated on smooth hot calender rolls whereby it is 30 sheeted into thin layers, preferably to the approximate gauge of frictioned cord fabric. This sheeted stock is then preferably subjected to a semi-cure which reduces it to the approximate pliability of frictioned cord 35 fabric and at the same time renders it less "tacky"—thus more easily handled. After the semi-cure, the sheets are again run through a second set of rollers especially surfaced to finish the sheet under pressure 40 whereby the stock emerges with its surface striated, fluted or grooved in the direction of its length, being the direction of original length as formed by its passage through the first hot roll calender. Immediately following this second surface rolling, the stock, 45 which now resembles cord fabric, is run through a calender for the purpose of receiving its surface coating of vulcanizable rubber, just as fabric stock is prepared for tire building. This surface coating process is only the usual and well recognized frictioning or skim coating operation whereby the unifying binder between ply and ply is affixed.

55 After the foregoing calender operations, the fully treated stock is cut on the bias, like any other straight grained stock, and in due course incorporated into the carcass with the same ease that attends the use of textile stock. The same apparatus for building and stitching is used, with the only apparent difference that the wholly rubber stock handles and stitches down with greater facility, due to its inherent property of increased pliability. In the building operation, the rub-

ber stock offers an added economy over fabric stock in that the inevitable trim-off is not wasted, but can be again milled and reclaimed, whereas the trim-off of fabric is practically a dead loss of considerable moment, due to its high relative price as compared with rubber.

Upon the completion of the building operation, the formed structure is cured in a conventional mold, either on an air bag, or in place on the building form upon which it was constructed. In the building process, it is, of course, feasible to apply additional members to the casing; such as special chafing strips around the bead and lower side 75 walls, a special stock tread of extremely tough material, or the like—all within the scope of my invention, which is limited to the main structure of the casing.

It has been proved, and the possibilities 80 of further development are practically untouched, that the physical properties of rubber can be greatly changed by chemical treatment. In fact, the tensile strength can be increased to such an extent that the product is admirably adapted to take the place of textile fabric in a casing, in the manner described; this increasing, by suitable well-known chemical processes, of the toughness and tensile strength of the rubber being, of course, contemplated as a necessary incidental step in my process. In addition to meeting the mere strength requirement, this rubber stock possesses many advantages over fabric when so employed. For instance, a 85 wholly rubber carcass is less liable to heat in service; will not stone bruise and blow out by internal rupture within reasonable limits; the component plies form a perfect union with each other and will not separate, 90 and will not rot out if moisture is introduced through a surface cut; there being great resistance to fatigue, the casing will not break down due to under inflation, like a fabric tire; a rupture or cut can be repaired with facility; and the entire manufacture, both as affecting the cost of labor and materials, is vastly less expensive than for the conventional tire.

With regard to the treatment of the sheeted stock for the purpose of serrating its surface in the direction of its strength grain, it is obvious that the configurations may take a great variety of form. The material could be intermittently slotted; stranded by completed severance; or merely fluted, or the like. The chief object being to roughen the surface in the direction of the rolled strength grain for the purpose of affording a suitable base for the subsequently applied vulcanizable friction treatment to adhere to in an effective manner. It is recognized that sheeted plastic material develops a well defined superior strength grain in the direction of its rolled or extruded length. This

principle is taken advantage of by my present conception, as explained, and the second operation of rolling surface impressions in the direction of the primary rolled grain tends to augment any strength advantage residing therein. In the application of the bias cut stock to the casing, in the building process, this direction of grain strength is utilized just as cord fabric is laid up.

10 In the treatment of the rubber stock, many variations will become apparent to an experienced rubber worker. For instance, the work could be done all on one calender to the elimination of the preferred double 15 process by originally sheeting out the stock on hot rolls, suitably designed to impress the surface of the stock with the linear features characteristic of my invention. Again, the surfacing could be done by a platen press 20 immediately following the primary calendering, and the press be heated whereby semi-vulcanization would result. Also, the stock might, in the first instance, be forced through a parallel slot in an extruding machine die whereby it is delivered in thread-like form to be loosely unified by passing direct through suitable rolls, or the like.

Having thus described my invention, and especially reserving all obvious variations 30 that could be availed of within the scope of the appended claims to accomplish the object sought to be protected, what I claim is:

1. The method of constructing a tire casing comprising the following steps: (a) sheeting a chemically toughened vulcanizable compound, (b) primarily heat treating the sheeted stock, (c) striating the surface of the primary heat treated stock in the direction of the sheeted grain, (d) bias cutting, and surfacing the stock with a vulcanizable unifying binder, (e) assembling the stock with the striæ in obliquely disposed arrangement into casing form in superposed plies, (f) curing the assembled structure.

45 2. The method of constructing a tire casing, comprising the following steps: (a) sheeting a chemically toughened vulcanizable compound whereby the surface is striated in the direction of the length of flow, (b) bias cutting the striated sheet into tire forming plies, (c) assembling the plies in simulation of cord tire stock methods obliquely of the circumference of the structure, (d) vulcanizing the assembled casing.

50 3. The method of constructing a tire casing of tough vulcanizable material simulating the property of textile tire insertions, comprising the following steps: (a) preparing a chemically toughened vulcanizable compound whereby stock is produced in sheets having surface striæ, (b) surface coating the stock with a unifying vulcanizable binder and cutting the stock into convenient 55 ply lengths for assembly, (c) assembling the plies in superposed relation with the striæ

obliquely laid on the circumference of the casing with alternating ply striæ oppositely directed, (d) vulcanizing the assembled casing.

4. The method of preparing a tire casing 70 composed of strength members wholly of rubber, comprising the following steps: (a) preparing building plies of a chemically toughened rubber compound in simulation of cord fabric with a definite grain in one 75 direction, (b) assembling the plies in union with a unifying medium in superposed relation, (c) vulcanizing the assembled structures.

5. The method of preparing a tire casing 80 composed of plies of semi-cured stock wholly of rubber, comprising the following steps: (a) sheeting a vulcanizable rubber compound chemically treated to impart physical 85 properties desirable for tire carcass plies whereby cord-like lines are formed in the direction in which the stock is worked, (b) cutting, surfacing and incorporating said plies into a carcass structure in simulation 90 of any well known method of casing building, (c) vulcanizing the assembled structure.

6. The method of building a tire casing of the class described, comprising: (a) preparing and sheeting an all-rubber compound 95 of high-tensile properties whereby a definite strength grain is established and maintained in one direction, (b) semi-curing the sheeted material whereby it is rendered less tacky, and deeply striating the surfaces thereof in 100 the direction of the grain, (c) bias cutting the stock with respect to the direction of the grain, (d) surface coating the bias cut stock with a highly elastic vulcanizable binder adapted to serve as a flexible unifying 105 cushion binder between ply and ply, (e) assembling the bias cut, coated, stock in casing form with the direction of grain obliquely disposed thereof, (f) unifying the assembled 110 structure by vulcanization.

7. The method of building a tire casing of the class described, comprising: (a) preparing and sheeting a chemically toughened all-rubber compound of high tensile properties whereby a preponderant strength grain is established and maintained in one direction, (b) rendering the prepared sheets less tacky by a subsequent operation and striating each surface thereof parallel with the strength 115 grain, (c) surface coating the stock with a 120 highly elastic, adhesive, vulcanizable binder adapted to flexibly unify and cushion ply and ply, (d) assembling the sheeted and coated stock in casing form whereby the direction of grain of each ply sheet is disposed obliquely thereof and at an angle to adjacent 125 assembled plies, (e) unifying the assembled structure by vulcanization.

In testimony whereof I affix my signature,
THOMAS C. MARSHALL.
